UNITED STATES PATENT OFFICE

JAMES WALTER ROBERTSON, OF DRYMEN, SCOTLAND

TWO-STROKE CYCLE INTERNAL COMBUSTION ENGINE

Application filed August 27, 1929, Serial No. 388,687, and in Great Britain September 5, 1928.

This invention relates to two-stroke cycle internal combustion engines.

In the operation of the normal type of two-stroke cycle internal combustion engine 5 in which transfer is effected at atmospheric pressure it is only possible to admit comparatively small weight of charge without incurring serious loss of fuel through the exhaust ports. The scavenging of such 10 an engine is imperfect; the provision of a deflector piston is objectionable; and the remoteness of the spark plug from the transfer ports prevents even firing at low speeds.

In two-stroke cycle engines of the type 15 having an air scavenge and subsequent transfer at atmospheric pressure, some only of these defects are overcome.

The type in which the transfer of the 20 charge is effected after the exhaust ports are closed is the most promising, but in this type it is necessary to effect at least a partial scavenge while the exhaust ports are open. To effect this scavenge by means 25 of air alone is difficult without undue complication and not wholly desirable.

The invention has for its primary object 30 to provide an arrangement whereby a small measured volume of fresh mixture may be used to effect partial scavenge while the exhaust parts are open, followed by transfer at super-atmospheric pressure after the exhaust ports are closed.

In the drawing Fig. 1 is a vertical transverse section of a two-stroke cycle internal 35 combustion engine according to the invention; Fig. 2 is a diagram showing the cycle of operations.

Referring to the drawing, 1 denotes the 40 upper barrel and 2 the lower barrel of a two-diameter cylinder formed with transfer passages 3 and fitted with a two-diameter sleeve 4 in which works a piston 5 having a flared skirt 6 adapted to operate in the enlarged lower end 4' of the sleeve 4. The 45 sleeve and piston reciprocate within the cylinder with the same frequency but out of phase. The trunk of the piston is fluted at 7.

The annular space 8 formed between the 50 piston skirt and the sleeve constitutes a

compressor cylinder which at a predetermined period during each cycle communicates with the cylinder proper by way of the transfer passages 3 and ports 9, 10 formed, respectively, near the upper end 55 and near the lower end of the top portion 4 of the sleeve and co-operating, in the operation of the engine, with the upper and lower ends of the transfer passages. 11 denotes exhaust ports formed in the sleeve 60 intermediate the ports 9, 10, and coacting, in the operation of the engine, with exhaust ports 12 formed in the cylinder wall intermediate the upper and lower ends of the transfer passages 3. The lower cylinder 65 barrel 12 is provided with an induction inlet passage 13 adapted to communicate with the compressor cylinder 8 under the control of inlet ports 14 formed in the enlarged lower end 4' of the sleeve. 15 denotes the cylinder 70 head fitted with a spark plug 16 and serving to seal the upper end of the sleeve. The combustion space 17 is suitably shaped to accumulate fresh charge at the spark plug 75 points to ensure even firing at low speeds, the upper ends of the transfer passage 3 being inclined to the cylinder axis.

The annular space 18 between the sleeve 80 and the cylinder is vented at 19 to the crank-case 20.

Referring to the diagram shown in Fig. 2, a cycle of operation is as follows:—

In the ascent of the piston from the bottom dead-centre B, the direction of rotation being indicated by the arrow A, the exhaust 85 ports 11 of the sleeve 4, which are still partially in register with the exhaust ports 12 of the cylinder, are closed at the point C by the top of the piston 5 and the lower transfer ports 10 of the sleeve which are 90 now in register with the lower ends of the transfer passages 3 are uncovered by the flutes 7 in the piston trunk. The piston ascends and transfer takes place over the angle α from the compressor to the working cylinder by way of the flutes 7, lower transfer ports 10, transfer passages 3 and the upper transfer ports 9, the streams of gas impinging on the spark plug 16. Transfer continues until, at the point M, 95 100

minimum volume is attained in the compressor. At the point M the sleeve closes both ends of the transfer passages 3, thus trapping a measured volume of highly compressed charge in the transfer passages. The piston travels slightly upwards towards top dead-centre T and ignition takes place, the upper transfer ports 9 in the sleeve being sealed by the junk head 15 and the sleeve exhaust ports 11 in the piston. The cylinder exhaust ports 12 are only fully closed by the sleeve by the time the piston is at the first stage of its descent. The sleeve exhaust ports 11 are uncovered by the piston and the cylinder exhaust ports 12 are then uncovered by the sleeve exhaust ports 11 at the point O. The sleeve inlet ports 14 are registering with the induction passage 13, having themselves been uncovered by the skirt of the piston in its downward travel, the opening to induction occurring as soon as the pressure in the compressor cylinder 8 has dropped to atmospheric. Induction takes place over the angle γ . The exhaust ports 11, 12 are still open, exhaust taking place over the angle β . The transfer ports 9, 10 are uncovering the ends of the transfer passages, the ports 10, however, being sealed by the piston. A measured volume of charge previously contained in the transfer passages 3 thus enters the cylinder at a point remote from the exhaust ports and effects a partial scavange. Scavange is effected over the angle δ up to the point C. The induction passage 13 is sealed by the sleeve, the exhaust ports 11, 12 are closed as before and the main charge is about to be compressed.

I claim:

A two-stroke cycle internal combustion engine comprising, in combination, a two-diameter cylinder provided with transfer passages, exhaust ports intermediate the upper and lower ends of said passages, and an inlet in the part of larger diameter, a two-diameter ported sleeve reciprocable in said cylinder, a piston having a fluted trunk and an enlarged skirt and reciprocable in said sleeve, said sleeve and said piston being adapted to reciprocate with the same frequency but out of phase with one another, and said skirt and said sleeve bounding an annular space constituting a compressor cylinder which is vented to the crankcase and which, at given times, is opened to said transfer passages and, at other times, to said cylinder inlet.

In testimony whereof I have signed my name to this specification.

JAMES WALTER ROBERTSON.
